CLAIM

The ornamental design for a shoe upper, as shown and described.

DESCRIPTION

FIG. 1 is a left side rear perspective view of a shoe upper in accordance with my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a right side rear perspective view thereof;

FIG. 9 is another left side rear perspective view thereof;

FIG. 10 is a left side view of the shoe upper in a stretched configuration thereof;

FIG. 11 is a top perspective view of the shoe upper thereof;

FIG. 12 is a top perspective view of the shoe upper in a stretched configuration thereof;

FIG. 13 is a top perspective view of the shoe upper in a partially stretched configuration thereof; and,

FIG. 14 is a top perspective view of the shoe upper in a partially stretched configuration thereof.

Broken lines shown in the drawing represent environmental structure of the shoe and form no part of the claimed design. The surfaces devoid of shading lines form no part of the claimed design.
